(57) **CLAIM**

The ornamental design for a glove, as shown and described.

DESCRIPTION

FIG. 1 is a perspective view of a glove, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of portion 8 in FIG. 1; and,

FIG. 9 is a perspective view in the use configuration.

The smaller-scale broken lines illustrate portions of the glove and form no part of the claimed design. The larger scale broken lines identify enlarged view areas and form no part of the claimed design.

1 Claim, 9 Drawing Sheets
